QUILTING FRAME

Sidney S. Russell, St. Louis, Mo.

Application July 30, 1936, Serial No. 93,477

2 Claims. (Cl. 45—24)

This invention relates to a quilting frame and it aims to provide a generally improved construction wherein the parts are quite durable and efficient, wherein adjustment and fastening of the rolls and the parts mounting them is effected in a novel manner, especially so as to maintain the quilt under tension and to accommodate the addition of cotton between the quilt and the lining, and a construction which may be readily disassembled so as to occupy small space when not in use.

The more specific objects and advantages will become apparent from a consideration of the description following taken in connection with accompanying drawings illustrating an operative embodiment.

In said drawing:—

Figure 1 is a view of the structure in side elevation, parts being broken away to disclose details;

Figure 2 is a central vertical sectional view taken substantially on the plane of line 2—2 of Figure 1;

Figure 3 is a detail section taken on the line 3—3 of Figure 2, and

Figure 4 is a fragmentary plan view illustrating the fastening of a quilt and a lining roll.

Referring specifically to the drawing wherein like reference characters designate like or corresponding parts, a quilting frame may comprise two uprights or standards 10 which are relatively narrow and either permanently or removably joined by a longitudinal strip 11, secured thereto, by brackets or angles 12, fastened by screws or bolts as at 13. At the lower ends, each upright may have a foot 14 removably secured thereto as by means of a removable bolt 15 and a pin 16 carried by each foot and adapted to enter a socket 17 in the upright. Casters 18 are preferably provided on the feet.

At the upper ends of the uprights 10 blocks or plates 19 are detachably fastened by means of removable bolts 20. Such blocks or plates are connected together by a pair of spaced apart bars 21 which bars and plates are connected together by means of brackets 22 screwed or bolted in place as at 23 and on two of which bolts, at each end of the device, struts 24 are pivoted. Said struts are preferably made of a single piece of wire or rod of resilient material and inter-mediate their ends are arched and extended upwardly as at 25 so as to embrace the strip or bar 11 from above and have a certain wedging action against the same to aid in rigidly connecting the parts together.

Adjacent the upper edges of the plates 19, angle

irons 26 are adjustably secured, the same having horizontal flanges 27 extending across the tops of the plates and vertical flanges 28 depending in spaced relation to the inner surfaces of such plates. Said inner surfaces also have strips 29 fastened thereto. A pair of adjustable bolts 30 pass through each of the flanges 28 and the strips 29.

In order to mount the quilting and lining rolls, four bars are employed as at 31. Such bars are removable and adjustable, having their inner ends located between the plates 28, flanges 27 and strips 29, their inward movement being limited by screws or pins 32 passed through the flanges 28 and into the plates 19.

Two of the bars 31 adjacent one end have notches 33 cut in from the top thereof and the other bars adjacent the outer ends have a pair of notches 34 cut inwardly from the tops thereof. In said notches, the reduced cylindrical ends or trunnions 35 of rollers 36, 37 and 38 are journaled. This construction enables the bars 31 and the rollers 36, 37 and 38 to be readily removed or disassembled for storage, packing or other purposes. To prevent accidental removal of the rollers, the outer ends of each of the bars are provided with holder members for the rollers designated 39. These elements 39 are pivoted as at 40 on vertical axes to the bars 31 and the elements are of angle shape in cross section so as to engage the upper and outer sides of the bars and in addition, at the free ends of the elements they are of U-shape so as to have extensions 41 which are resilient and which will frictionally grip the ends of the bars 31 to hold the elements 39 against accidental displacement.

Around the roller 36, the quilt 42 and the lining 43 are wrapped. Additionally, the quilt is wrapped about the roller 38 while the lining is wrapped about the roller 37. All of the rollers 36, 37 and 38 are provided with a ratchet wheel 44 thereon and pawls 45 are pivoted at 46 on the arms, to engage the ratchet wheels in order to prevent unwinding of the material therefrom as shown.

The bars 31 may be readily adjusted through the loosening and tightening of the bolts 30 as when the quilt runs irregular, in order to apply the desired tension at any corner or corners of the device. In addition, the novel means which secures the rollers 37 and 38 in place enables them to be quickly released for the proper operation when padding with cotton according to the process of quilting, to avoid roughness and lumpiness in the completed quilt.

50

55

55

It will be realized that the frame comprises parts which may be readily disassembled or detached in order to occupy minimum space when not in use.

5 I claim as my invention:—

1. Apparatus of the class described having uprights, a strip connecting the uprights, a quilting frame having depending plates, means connecting the plates to the uprights, U-shape resilient struts having their free ends pivotally connected to the plates, said struts intermediate their ends and at the lowermost portion being arched whereby they are resiliently engageable with the strip.

2. Apparatus of the class described having uprights, a strip connecting the uprights, a quilting frame having depending plates, means connecting the plates to the uprights, U-shape resilient struts having their free ends pivotally connected to the plates, said struts intermediate their ends and at the lowermost portion being arched whereby they are resiliently engageable with the strip, bars connecting said plates on opposite sides of the uprights, and said struts being directly pivoted to said bars. 5

SIDNEY S. RUSSELL.
